TYPEWRITER

Carl L. Otto, New York, N.Y., assignor to Litton Business
Systems, Inc., a corporation of New York

Filed June 21, 1967, Ser. No. 7,547

Term of patent 14 years

(Cl. D64—11)

Fig. 1

FIG. 1 is a perspective view illustrating the front and right side of the typewriter embodying my new design; and

FIG. 2 is a perspective view illustrating the rear and left side of the typewriter shown in FIG. 1.

The essential features of the design reside in the portions shown in full lines on the drawings, conventional keys and other conventional elements being shown in broken lines.

I claim:

The ornamental design for a typewriter, substantially as shown and described.
